UNITED STATES PATENT OFFICE.

JOHN WOTOCEK, OF CHICAGO, ILLINOIS, ASSIGNOR TO E. L. MANSURE COMPANY, OF CHICAGO, ILLINOIS, A CORPORATION OF ILLINOIS.

DESIGN FOR SCALLOP BULLION FRINGE.

Application filed May 21, 1924. Serial No. 9,670. Term of patent 7 years.

To all whom it may concern:

Be it known that I, JOHN WOTOCEK, a citizen of the United States, residing at Chicago, Cook County, Illinois, have invented a new, original, and ornamental Design for Scallop Bullion Fringe, of which the following is a specification, reference being had to the accompanying drawing, forming part thereof.

The figure is a face view of a scallop bullion fringe showing my new design.

I claim:

The ornamental design for scallop bullion fringe as shown.

JOHN WOTOCEK.
